UNITED STATES PATENT OFFICE

MABS RYDEN AND INEZ E. SCHRODT, OF LOS ANGELES, CALIFORNIA; SAID SCHRODT
ASSIGNOR TO SAID RYDEN.

GARMENT

Application filed January 28, 1932. Serial No. 589,453.

This invention relates to an improved garment adapted to completely and snugly cover the body from the waist down to the upper portion of the thighs without restricting freedom of movement. The garment is particularly adapted for use as an undergarment for women, although it may also be used for bathing, dancing, etc., depending upon the type and character of material employed. Heretofore, pants, shorts or trunks have been made but such prior garments were either so loose as to cause wrinkles and bulges when worn under close-fitting gowns, or they would crawl and shift on the body of the wearer. Furthermore, the garments of this character made heretofore incompletely covered the gluteus maximus muscles or uncovered said muscles when the wearer rapidly changed her position, thereby pinching said muscles and causing unsightly bulging and discomfort. Furthermore, the garments of the prior art have not been constructed in such manner as to completely cover the pubic regions at all times. We have discovered that by employing a novel arrangement of elements and by forming the elements in a particular relation to each other, a garment is produced which is free of all the prior disadvantages and instead has the property of completely covering the hips and pubic region even when the wearer is performing acrobatic stunts or otherwise vigorously exercising without simultaneously restricting the movements or causing discomfort to the wearer. One of the distinguishing characteristics of the garment of this invention is that it completely covers and restrains the gluteus maximus muscles and extends downwardly so as to cover the upper portions of the muscles biceps flexor cruris, tensor fasciae femoris and rectus cruris. A garment made in accordance with our invention fits the body of the wearer very snugly without binding or chafing and does not shift or crawl during strenuous exercise. By extending down to the muscles stated hereinabove, the garment of this invention permits a woman to wear a very close-fitting gown without the formation of wrinkles or bulges; when the garment of our invention

is worn as a pair of dancing or bathing trunks, the pubic regions remain thoroughly covered without in any way restricting the movements of the wearer.

An object of this invention is to disclose and provide a garment which is designed and formed so as to fit the person closely without restricting free movement and without shifting upon or chafing the person of the wearer.

A further object is to produce a pair of pants which will be close fitting and will not therefore be visible through the tightset evening gowns.

Another object is to provide means whereby shadowing will not be obvious.

A further object is to produce pants which will be comfortable to the wearer, and one which will not crawl between the limbs.

Other objects and advantages will be apparent during the course of the following description.

In the accompanying drawing forming a part of this specification and in which like numerals are employed to designate like parts throughout the same,

Fig. 1 is a front view of our pants as the same would appear in use,

Fig. 2 is a three-quarter side view as the same would appear in use,

Fig. 3 is a rear view of the same in use,

Fig. 4 is a perspective view of our garment, looking at the front thereof,

Fig. 5 is a similar view looking at the rear thereof,

Fig. 6 is a plan view of the blank from which our garment is formed, and

Fig. 7 is a plan view of a re-inforcing portion of the garment.

The drawing illustrates a garment for use particularly by dancers and acrobats, which garment is in the form of pants, which will give complete protection to the wearer, yet at the same time affording freedom of movement especially of the rectus femoris muscle, or that one most use by all dancers in high kicks. These pants may be cut from material and on the bias of the material, which allows the garment to be snugly fitted and yet permits of a flexibility needed by the body in taking quick changes. The double

portion in the front affords longer wear and prevents any shadows. The garment may be closed in the center of the back which closing brings the hooks or eyes to such a position 5 that they sink into the natural body crevice between the buttocks. The waistline and leg openings are preferably bound with tape and elastic may be run through this tape, if necessary.

10 It is a well known fact that some of the evening gowns are so close fitting that it is impossible to wear any kind of a garment underneath. However, with this garment it is possible to wear the tightest evening gown 15 and still have smooth moulded-to-the-body contours without any sort of wrinkles, lumps or shadows.

In the accompanying drawing wherein for the purpose of illustration is shown a preferred embodiment of our invention, the 20 numeral 4 designates the front portion whereas 5 designates the rear portion of a garment in extended form or a blank of material cut upon a bias and having the general 25 contour shown in Fig. 6. The margin 6 forms the front of the waist portion and the margin 7 forms the back of the waist portion. This margin 7 is interrupted by darts 8 and 9, which darts permit the forming of the garment 30 to the body. The back margin is also slit as shown at 11 so that the garment may be drawn on over the hips and afterwards secured by any convenient fastening means, as for instance, as shown at 12 in Fig. 5. A 35 protecting strip 13 protects these fastening means from coming into contact with the body. The front portion 4 is provided with outwardly flaring side margins 14 and 17, whereas the rear portion 5 is provided with 40 outwardly flaring side margins 16 and 18 directed toward the front portion 4. The margins 14 and 16 are stitched together so as to form one side seam of the garment and the margins 17 and 18 are stitched together 45 so as to form the other side seam of the garment. The openings or bays 19 and 21 will form the leg openings A and B (see Fig. 4). These leg openings or bays substantially 50 separate the front and rear portions 4 and 5 respectively of the garment, the inner portions of the legs bays 19 and 21 being separated by a crotch portion 23. The leg bays 19 and 21 extend from the side margins 17 and 18 and 14 and 16 respectively, upward- 55 ly toward the waist margin 6 of the front portion 4. It is to be noted that the distance between opposing termini of side margins at each leg bay is less than the length of the side margins. In other words, the distance 60 between the points 24 and 25 is less than the length of the margins 14, 16, 17 or 18. This particular arrangement insures the production of a garment which will completely cover the hips of the wearer and extend downward- 65 ly at the sides and rear so as to entirely cover

the gluteus maximus muscle without impairing freedom of movement. A diamond or shield-shaped piece 22 provided with enlarged and pointed end portions 26 and 27 is stitched to the crotch portion 23, the pointed and enlarged heads 26 and 27 extending into the front and rear portions 4 and 5 of the garment. This piece 22 insures a thorough covering of the pubic region and of the rectal cavity so as to prevent shadows and 70 impart smoother lines.

If desired the garment may be made entirely of jersey material or of material of an elastic nature of sufficient "give" so that the garment may be readily slipped on or off 80 without unhooking a belt, thus eliminating the hook and eye arrangement. When elastic materials of this nature are employed, it is not necessary to cut the material on the 85 bias.

It will thus be seen that we have provided a garment which is cut from a single piece of material and cut upon a bias and one which when stitched together will form a garment 90 which will have all the advantages above set forth.

It is to be understood that the form of our invention herewith shown and described is to be taken as a preferred example of the same and that various changes relative to the material, size, shape and arrangement of parts 95 may be resorted to without departing from the spirit of the invention or the scope of the subjoined claims.

Having thus described our invention, we 100 claim:—

1. In a garment, a blank of material, said blank having a front margin and a back margin and side margins, said side margins being interrupted by openings extending diagonally thereinto toward said front margin in such a manner that when said side margins are folded upon themselves and stitched said openings will form leg holes, and a shadow-proofing piece attached to said blank and extending between said openings. 105

2. A garment capable of closely fitting the body from the waist and over the hips to the upper portion of the thighs, comprising: a front portion provided with a relatively narrow waist margin, outwardly flaring side margins and inwardly directed leg margins inclined toward said waist margin from said side margins; and a rear portion provided with a relatively narrow waist margin, outwardly flaring side margins adapted to be connected to the side margins of the front portion, and inwardly directed leg margins inclined away from the waist margin of said rear portion, said front and rear portions being connected together by a crotch portion. 115

3. A garment capable of closely fitting the body from the waist and over the hips to the upper portion of the thighs, comprising: a 120

- front portion provided with a relatively narrow waist margin, outwardly flaring side margins and inwardly directed leg margins inclined toward said waist margin from said 5 side margins; a rear portion provided with a relatively narrow waist margin, outwardly flaring side margins adapted to be connected to the side margins of the front portion, and inwardly directed leg margins inclined away 10 from the waist margin of said rear portion, said front and rear portions being connected together by a crotch portion, and a shield-shaped member provided with an enlarged upwardly pointed head extending into the 15 front portion of the garment and adapted to cover the pubic region and an enlarged upwardly pointed head extending into the rear portion of the garment carried by said crotch portion. 20 4. A garment capable of closely fitting the body from the waist and over the hips to the upper portion of the thighs, which in extended form comprises: a front portion provided with a waist margin and outwardly flaring 25 side margins; a rear portion provided with a waist margin and outwardly flaring side margins directed toward the front portion; and leg bays separated from each other by a crotch portion, substantially separating 30 said front and rear portions and extending from the side margins upwardly toward the waist margin of said front portion, the distance between opposing termini of side margins at each leg bay being less than the length 35 of said side margins. 5. A garment capable of closely fitting the body and upper portion of the thighs, comprising: a front portion provided with a relatively narrow waist section, outwardly flaring 40 side margins, and inwardly directed leg margins inclined toward said waist section from said side margins; a rear portion provided with a relatively narrow waist section, outwardly flaring side margins adapted 45 to be connected to the side margins of the front portion, and inwardly directed leg margins inclined away from the waist section of said rear portion; a crotch portion connecting said front and rear portions, and 50 a shielding member provided with an enlarged head extending into the front portion of the garment and adapted to cover the pubic region and an enlarged head extending into the rear portion of the garment carried 55 by said crotch portion. 6. A garment capable of closely fitting the body including a front and a rear portion, said front and rear portions being separated by a unitary crotch portion connected to the 60 front and rear portions, said unitary crotch portion being provided with an enlarged head extending into the front portion of the garment and adapted to cover the pubic region, an enlarged head extending into the rear portion of the garment, and a narrow portion 65
- between said heads and integral therewith, said narrow crotch portion being free from seams, said garment formed with leg openings extending diagonally toward the front portion and terminating in the crotch portion. 70 7. A garment capable of closely fitting over the hips and upper portion of the thighs of the wearer, comprising a front portion provided with a relatively narrow waist section, outwardly flaring side margins, and inwardly directed leg margins inclined toward said waist section from said side margins; and a rear portion provided with a relatively narrow waist section, outwardly flaring side margins adapted to be connected to the side 75 margins of the front portion, and inwardly directed leg margins inclined away from the waist section of said rear portion, said front and rear portions being connected together by a crotch portion whereby leg bays are formed by opposing leg margins of front and rear portions substantially separating said front and rear portions and extending from the side margins upwardly toward the waist section of said front portion. 80 8. A garment capable of closely fitting the body from the waist and over the hips to the upper portion of the thighs, which in extended form comprises: a front portion provided with a waist margin and outwardly flaring side margins; a rear portion provided with a waist margin and outwardly flaring side margins directed toward the front portion; and leg bays separated from each other by a crotch portion, substantially separating said front and rear portions and extending from the side margins upwardly toward the waist section of said front portion. 85 9. In testimony whereof we affix our signatures. 90
